UNITED STATES PATENT OFFICE.

BURT R. VAN VALKENBURG, OF OAKLAND, CALIFORNIA.

TREMOLO MECHANISM.

1,085,308.

Specification of Letters Patent.

Patented Jan. 27, 1914.

Application filed July 26, 1912. Serial No. 711,635.

To all whom it may concern:

Be it known that I, BURT R. VAN VALKENBURG, citizen of the United States, residing at Oakland, in the county of Alameda 5 and State of California, have invented certain new and useful Improvements in Tremolo Mechanisms, of which the following is a specification.

This invention relates to musical instruments of the type used in connection with perforated music sheets and has special reference to a means for producing a tremolo effect in connection with such instruments.

The principal object of the invention is 15 to provide a novel form of valve for use in connection with instruments of this class so arranged that the same may be opened and closed repeatedly in a rapid manner thereby actuating the musical instrument to produce 20 a tremolo effect such as is employed in beating a snare drum, producing an imitation of the vox humana stop in connection with a set of organ pipes.

With the above and other objects in view, 25 the invention consists in general of certain novel constructions, combinations and arrangements of parts as will be hereinafter fully described, illustrated in the accompanying drawings, and specifically claimed.

30 In the drawings—Figure 1 is a front elevation of a player piano partly broken away showing the device used in connection with a drum mounted on the top of the piano. Fig. 2 is a cross section through a valve used 35 in connection herewith. Fig. 3 is a valve which is located on the key slip of the piano for controlling the valve shown in Fig. 2. Fig. 4 is a rear elevation of the tremolo device. Fig. 5 is a front view with the cover 40 plate removed. Fig. 6 is a transverse section through the tremolo device.

The casing of the piano used herewith is indicated at 10 and this piano is of the ordinary player type, the mechanism of which it 45 is not deemed necessary here to be shown as the same forms no part of the present invention. The casing is provided with the usual key slip 11 and on top of the piano there is located a drum 12 in front of which 50 is positioned a tremolo device indicated in general at 13. This tremolo device 13 consists of a bellows having a stationary side 14 firmly fixed in position on the top of the piano and to this stationary side is hinged 55 a movable side 15, the two sides being connected by suitable flexible walls 16.

Extending through the side 14 is an opening 17 on each side whereof is located a bridge plate 18 and each of these bridge plates is provided with openings 19 for the 60 passage of air. Through the bridge plate 18 extends a valve stem 20 and on this stem on the outside of the casing is a valve 21. In order to limit the movement of the valve in an outward direction there is provided a 65 stop member 22. Secured to the sides of the bellows is a spring 23 which normally holds the bellows in an open position and within the bellows there is provided a leaf spring 24 which has one end secured to the movable 70 side 15 adjacent its hinged wall; the other end projects over the end of the valve stem 20. The position of this end with relation to the valve stem 20 when the bellows is distended is regulated by means of an adjusting screw 25 while the extent to which 75 the bellows will collapse is regulated by means of an adjusting screw 26 which passes through the movable side of the bellows and bears against the spring adjacent the valve 80 stem 20 when the bellows is collapsed.

Secured to the movable side 15 is a drum stick 27 provided with a head 28 adapted to contact with the sheep skin covering the drum. This bellows is connected by means 85 of a pipe 29 to a valve box 30 which is provided with a chamber 31 connected by means of a pipe 32 with a source of vacuum 33, the specific means not being deemed necessary here to be shown as the same forms no part 90 of this invention. Leading from this chamber 31 to the open air is a passage 34 and the pipe 29 communicates directly with this passage and by means of the passage with the chamber 31. On each side of the opening 34 is a bridge plate 35 similar to the bridge plates 18 and through these bridge plates passes a valve stem 36 carrying between the plates a valve 37 arranged to close either end of the opening 34. 100

Extending from the chamber 31 is a cell 38 which is cut off from the chamber by means of a flexible diaphragm 39 against which the lower end of the valve stem 36 bears. Connected with the cell 38 are passages 40 and 41; the passage 40 is connected by means of a tube 42 with a tracker board 43 forming part of the automatic playing mechanism. The passage 41 is connected by a tube 44 with a valve box 45 having an 110 opening 46 with which the tube is connected and this opening is normally held closed by

means of a valve 47 carried on a lever 48 which is constantly urged in the direction of the opening 46 by a spring 49. This valve 5 box 45 is located beneath the key slip 11 of the piano and extending upward through the slip is an operating button 50 which controls the opening and closing of the valve 47, being connected at its lower end to the lever 48.

10 In the operation of this device whenever pressure is reduced in the cell 38 by means of opening one of the passages 40 or 41 to the air either through the medium of an opening in the music sheet as indicated at 15 51 or by opening the valve 46 the valve 37 will close the outer end of the opening 34 and open the inner end. This will place the interior of the bellows in communication with the vacuum device and when this is 20 done the bellows will collapse. As soon as the bellows collapses the spring 24 will strike the valve stem 20 and open the valve 21. This will allow a rush of air under atmospheric pressure to expand the bellows immediately upon which the valve 21 will close 25 and the vacuum will again operate to collapse the bellows. These alternate actions will take place with a rapidity depending on the amount of collapse that the bellows 30 has so that they can be regulated by properly positioning the screws 25 and 26 as they will also depend on the time in which the valve 21 opens. Thus the drum stick 27 will be rapidly vibrated and the drum beaten. There 35 has thus been provided a simple and efficient device of the kind described, and for the purpose specified.

Having thus described the invention, what is claimed as new, is:—

40 1. In a device of the kind described, a fixed bellows side having an opening therethrough, and a passage adapted for connection to a vacuum tube, an outwardly opening valve controlling said opening, a moving 45 able bellows side hinged to the fixed side, a flexible wall connecting said sides, a stem on said valve projecting within the chamber formed by said sides and wall, a leaf spring having one end connected adjacent the hinge

of the movable side and the other end lying 50 adjacent the valve stem, and means to adjust said spring.

2. In a device of the kind described, a fixed bellows side having an opening therethrough, and a passage adapted for connection to a vacuum tube, an outwardly opening valve controlling said opening, a moving 55 able bellows side hinged to the fixed side, a flexible wall connecting said sides, a stem on said valve projecting within the chamber 60 formed by said sides and wall, a leaf spring having one end connected adjacent the hinge of the movable side and the other end lying adjacent the valve stem, means to adjust said spring, a screw passing through said movable side and bearing constantly against the spring, and a second screw passing through said movable side and adapted for engagement by the spring when the latter strikes the valve stem. 70

3. In a device of the kind described, a fixed bellows side having an opening therethrough, and a passage adapted for connection to a vacuum tube, an outwardly opening valve controlling said opening, a moving 75 able bellows side hinged to the fixed side, a flexible wall connecting said sides, a stem on said valve projecting within the chamber formed by said sides and wall, a leaf spring having one end connected adjacent the hinge 80 of the movable side and the other end lying adjacent the valve stem, means to adjust said spring, a screw passing through said movable side and bearing constantly against the spring, a second screw passing through 85 said movable side and adapted for engagement by the spring when the latter strikes the valve stem, and a spring connected to said sides and arranged to constantly urge the free end of the movable side away from 90 the fixed side.

In testimony whereof I affix my signature in presence of two witnesses.

BURT R. VAN VALKENBURG.
